United States Patent Office.

N. B. ALLEN, OF NEWPORT, RHODE ISLAND.

Letters Patent No. 60,661, dated January 1, 1867.

IMPROVED BOAT-DETACHING APPARATUS.

The Schedule referred to in these Letters Patent and making part of the same.

TO ALL WHOM IT MAY CONCERN:

Be it known that I, N. B. ALLEN, of Newport, in the county of Newport, and State of Rhode Island, have invented a new and improved Device for Detaching Boats; and I do hereby declare that the following is a full, clear, and exact description thereof, which will enable others skilled in the art to make and use the same, reference being had to the accompanying drawings, forming part of this specification.

The object of this invention is to provide a most simple and substantial device, whereby a boat can be safely launched under all circumstances, whether the ship to which it is attached is under full speed or not. I am aware that many devices have already been invented for the aforesaid purpose, but they were all too complicated or not strong enough, and not convenient enough to handle.

My invention consists in providing each one of two metal rods, which extend from the middle of the boat to either end of the same, with a hook at their outer end. By securing their inner end to one lever, these bars or rods are by that lever always turned the same direction and manner. The tackles, which connect the boat with the davits, are secured to the boat by attaching them to the hook, by which they will be held as long as the point of the hook is turned down. As soon as a man amidship the boat turns the lever, the hook is turned up and both ends of the boat are disengaged simultaneously from the tackles. This device is so simple that it cannot possibly get out of order; it works very satisfactorily, and is very easily attached to new boats as well as to old ones of whatever description. There are no springs or small traps to rust or be disabled by long use. A boat which is provided with this apparatus can be conveniently laid up on the deck of a vessel, and, whenever it is needed, the apparatus will be ready for service. In the annexed drawing my invention is illustrated—

Figure 1 representing a vertical longitudinal section of a boat, which is provided with my improved apparatus.

Figure 2 is a plan or top view of the middle portion of the boat, showing the lever by which the apparatus is operated.

Figure 3 is a part of a vertical longitudinal section of a boat, which is provided with an apparatus which is a modification of my invention.

Similar letters of reference indicate like parts.

The bars or rods, A, which are made of any suitable kind of metal, are secured to the bolt by staples *a* and journals *b* in such a manner that they can turn freely within said staples and boxes. The bars A are connected amidship by a bifurcated lever, B, which is firmly secured to each bar, so that by turning the lever both bars are turned also. At the outer end of each bar, A, is arranged a hook, C, by which, when it is turned down, as in fig. 1, the boat is secured to the tackle. As soon as the bars A are revolved by means of the lever, B, so that the hooks C point up, both ends of the boat (or rather both hooks) will be simultaneously disengaged from the tackle. If it should be found objectionable to let the bars A run diagonally alongside the centre of the boat, the said bars may be arranged as shown in fig. 3, where they are kept on the bottom of the boat. The bar, D, in fig. 3, is provided with a pinion, E, which meshes into a pinion, F, on the bar G. The latter is provided with the hook C. By revolving the bar D in the same manner as the bars A, the hook C will be turned and the same result will be effected as is done by using the simple bars A.

What I claim as new, and desire to secure by Letters Patent, is—

The hooks C, which are secured to the bars A, (or their equivalent D E,) and which are operated by the lever B, substantially as and for the purpose herein shown and described.

N. B. ALLEN.
